BUTTON STRIP RETAINING MEANS

Emil A. Winnewisser, East Syracuse, N.Y., assignor to
Ward Industries Corporation, Syracuse, N.Y., a corpora-
tion of Delaware

Filed Aug. 16, 1957, Ser. No. 678,630

5 Claims. (Cl. 269—153)

This invention relates to a clamp assembly attachment to a folding machine, and more particularly to a clamp adapted to retain in position the button strips of a shirt placed on the folding table of a machine for the folding of said shirt.

Heretofore, various garment folding machines have been presented for the folding of laundered and cleaned garments. In the case of shirts and the like, means such as expanding collar formers have been employed to retain the shirt in position after it has been placed on the folding table of the machine. Since only the collar button is fastened prior to folding, the button strips have a tendency to spread apart during the folding operations, so that the finished folded shirt has the front open and is subsequently folded with the various portions of the garment in misalignment. For the operator of the machine to take time to button other buttons of the shirt is time consuming and therefore expensive.

It is accordingly the primary purpose of this invention to provide a clamp assembly for holding the button strips of a foldable garment in intended position during the folding operations of a folding machine.

It is a further object of the invention to provide a clamp of the above nature which is easily installed on any shirt folding machines of the type described, and which affords great ease of alignment of the button strips prior to the clamping, and which clamp assembly is quickly and easily released, allowing easy removal of the folded article therefrom.

According to this concept, a clamp is provided for attachment to an automatic shirt folding table such as the machine disclosed in Patent Number 2,508,108. A clamp arm with a toggle clamp lever attached thereto is provided. The operator of the machine places the button strips of the garment in position and presses downwardly on the clamp lever, retaining the strips in their intended position.

The above and further advantages will become apparent when the following specification is read with reference to the accompanying drawings, in which:

FIGURE 1 is front elevation of the clamping assembly.

FIGURE 2 is a side elevation of the clamping assembly, viewing from right to left of FIGURE 1.

FIGURE 3 is an enlarged elevation of the clamp arm assembly.

FIGURE 4 is a perspective view of an automatic shirt folding machine, details omitted, showing the displacement of the clamping assembly in relation to a shirt placed for folding.

The button strip clamp is adapted to be placed in the top of an automatic shirt folding table such as the one disclosed in Patent Number 2,508,108, the button strip clamping unit being placed near the bottom or tail end of the table and in alignment with the position of the button strips of a shirt placed thereon for folding.

The clamping assembly is mounted on a supporting bracket 3, suitably shaped of heavy gauge sheet metal or the like, and fastened to the front of the table with the clamp extending through the surface thereof. A slot cover 5 is adapted to fill in the opening or slot cut into the table surface 4 of the folding machine. With the assembly installed on the folding machine 40, FIGURE 4, the slot cover 5 will be substantially in the same plane or otherwise flush with the surface 4 of the folding table.

2

The clamp arm 14 of the present modification of the assembly is pivotally attached to the bracket 3 at 15 by a suitable roll pin or other means. The arm 14 is shaped with right angle bends so that it may project through an opening in the slot cover 5 and above the surface 4 of the folding table. The opposite end of the arm 14 is bifurcated and has a pin 13 therethrough for receiving the clamp lever 10, which lever 10 is in the shape of a toggle. The end portion 11 of lever 10 is heavier than end 12, or is otherwise balanced so that the lever 10 which pivots freely on the pin 13 will be weighted at end 11. The end portion 12 is slightly enlarged in dimension so as to engageably contact an excavated portion 16 of arm 14, as shown in FIGURE 1.

15 A second support bracket 2, fastened to bracket 3, supports the locking and releasing assembly. This assembly comprises mainly left hand spring-held arm 20 and right hand spring-held arm 21 pivotally mounted to bracket 2 on pins 25 and 26 respectively. A tension spring 23 is 20 tensionally supported between suitable pins at the outside ends of spring-held arms 20 and 21. The spring-held arms 20 and 21 have inner ends overlapping and bifurcated as at 22 in FIGURE 1, and a pivot pin 24 is slidably disposed therat. This pivot pin 24 is fastened to 25 an upstanding link member 28 so that the link 28 and the pin 24 are slidable vertically as a unit. Link 28 is pivotally attached at its upper end to a second link 29. Link 29, at its other end, is pivotally mounted at 15, and is adapted so as to pivot at 15 in unison with clamp 30 arm 14 for lifting the arm, as will be further described. A manual release handle 27 is fastened at one end of spring-held arm 21.

The whole assembly is provided with an automatic release assembly for attachment to the air pressure supply 35 used with most garment folding machines. This assembly 30 comprises a resilient diaphragm 31 supported between a hollow upper shell 32 and hollow lower shell 33 fastened together by screws 35. A fitting and hose 34 fastened at the bottom shell 33 lead to the source of air 40 under pressure (not shown), and admit this air pressure to the underside of diaphragm 31. The upper shell 32 has a portion upstanding and threaded so as to be threadably and adjustably engaged through an opening in the bracket 3. A plunger 38 has its bottom end resting on the upper surface of diaphragm 31 and is disposed in the upstanding portion of upper shell 32 so that the upper end of the plunger 38 engages the bottom of link 28. The height of the travel of the plunger may be regulated by 45 adjusting the disposition of the upstanding portion of shell 32 at the bracket 3, upon which the whole assembly 30 is locked in position by collar 37 and set screw 36.

The spring-held arms 20 and 21 are so arranged as to engage a pivot pin to releasably maintain the links 28 and 29 in an upward or downward position, so as to subsequently place the clamp arm 14 in an upward or downward position. FIGURE 1 illustrates the limits of vertical travel of the slideable pivot pin 24 as shown at references 24 and 24A. It is seen that the spring arms in their illustrated positions in FIGURE 1 lie with their outer ends pointed at an angle above a horizontal. The pivot pin is accordingly located at point 24, and spring 23 maintains tension on the spring-held arms to retain them in position. When the handle 27 (FIGURE 1) is moved to the left as indicated by the arrow, the arms 55 pivot about pins 25 and 26, placing the pivot pin in the position indicated at 24A. The outer ends of the spring-held arms 20 and 21 will then lie in a complementary position to the position illustrated, with the arms pointed at an angle below the horizontal. This will result in the link 28 being moved vertically upward, pivoting the link 29 upwardly and thus moving clamp arm 14 off the table, as seen in FIGURE 3. It is obvious that should auto- 60 65 70

matic operation be desired, the application of air pressure within the bottom shell 33 to the underside of diaphragm 31 will lift the diaphragm and thus raise the plunger 38 against the bottom of link 28. The link 28, by means of plunger 38, will thus move the spring-held arms to their complementary position instead of the handle 27. The spring-held arms are placed in the position shown in FIGURE 1 by manual pressure on the clamp lever 10 by the operator.

Having described the mechanical operation of the various elements of the assembly, the operation of the assembly within a machine for folding a shirt will now be described.

The assembly is installed in a shirt folding table 4 as shown in FIGURES 1 and 4, with the spring-held arms in the position so that the clamp arm 14 and clamp lever 10 are in the position in FIGURE 3. The shirt is placed face down on the table in the conventional manner, and the collar button has at this time been buttoned. The collar is positioned over the collar former and retained in position thereat. For purposes of illustration, the shirt in FIGURE 4 has been shown with the back cut away, exposing the button strips, herein referred to as the button strip 6 and the button hole strip 7. Having positioned the shirt 41 on the machine, the operator lifts the tail of the back portion of the shirt and grasps the button strips, placing the button strip 6 in the excavated portion 16 of clamp arm 14 as shown in FIGURE 3. The operator then places the button hole strip 7 on the table under the clamp arm 14 at the position shown in FIGURE 3. It is seen that the button strips overlap each other. Due to the pull on the bosom of the shirt during the folding operation, the button strips tend to pull apart. Therefore, because of the crossing of the strips before folding, the result after folding is that the button strips are substantially straight. This is generally conceded in the art as the best manner of presenting neat, uniformly folded shirts, especially where the body of the shirt is full-cut. The operation of placing the button strips is accomplished substantially simultaneously by the operator. After the button strips are placed, the operator manually presses down on the clamp lever 10, moving the spring-held arms 20 and 21 to their complementary positions in FIGURE 1. The end 12 of lever 10 contacts and retains the button strip 6 in position, the button hole strip 7 being retained in position by the clamp arm 14. A small specially shaped leaf spring 8, FIGURE 1, protruding through a slot (not shown) in the cover 5 bears on the underside of the strip 7 to aid in retaining it in position.

After the shirt form or plate 42 is in place on the shirt and the button strips are in place, air under pressure passes to the automatic release assembly 30. This occurs before folding blade 47 folds the tail portion of the shirt or folding mechanism 43 operates to fold the arm portion of the shirt. The manual release 27 is for the purpose of releasing the clamp if the button strips have been misplaced prior to folding of the shirt.

As hereinbefore mentioned, the weighted or counterbalanced end 11 of lever 10 maintains the end 12 of lever 10 in disengagement with the clamp arm 14 when the arm is in the position shown in FIGURE 3.

Having described a particular embodiment of my in-

vention, it is to be understood that the invention is not to be limited to the structure shown, but that modifications may be made which do not depart from the spirit and scope of the appended claims.

5 I claim:

1. A button strip clamp for a shirt folding machine having a working surface comprising supporting means adapted to be fastened to said folding machine, a clamp arm pivotally attached to said supporting means and having a portion adapted to extend over and engage the said surface, a clamp lever pivotally attached intermediate its ends to said clamp arm portion, said clamp lever having one end adapted to extend below said clamp arm portion, and means operable to move said clamp arm downwardly into engagement with said working surface and the said clamp lever into engagement with said clamp arm.

2. A button strip clamp for a shirt folding machine having a working surface comprising a supporting means 10 adapted to be fastened to said folding machine, a clamp arm pivotally attached to said supporting means and having a portion adapted to extend over and engage the said surface, a clamp lever pivotally attached intermediate its ends to said clamp arm portion, said clamp lever having one end adapted to extend below said clamp arm portion, and means operable to move said clamp arm downwardly into engagement with said working surface and the said clamp lever into engagement with said clamp arm.

15 3. A button strip clamp for a shirt folding machine as defined in claim 2, and pressure operated release means operably engaging said spring held means for releasing said clamp lever from engagement with said clamp arm.

20 4. A button strip clamp for a shirt folding machine having a working surface comprising supporting means adapted to be fastened to said folding machine, a clamp arm pivotally attached to said supporting means and having a portion adapted to extend over and engage the said surface, a clamp lever pivotally attached intermediate its ends to said clamp arm portion, said clamp lever having one end adapted to extend below said clamp arm portion, actuating means operable to move said clamp arm downwardly into engagement with said working surface and the said clamp lever into engagement with said clamp arm, and pressure operated release means operably engaging said actuating means for releasing said clamp arm and said clamp lever.

25 5. A button strip clamp for a shirt folding machine as defined in claim 4, said pressure operated release means including a diaphragm and a plunger operably connected 30 with said actuating means.
